PINKING MACHINE

Harry C. Herschman, Wheaton, Ill.

Application November 14, 1936, Serial No. 110,917

6 Claims. (Cl. 164—64)

This invention relates to pinking machines for cutting a wavy non-ravelling edge in fabric articles. In garments, a generous strip of fabric is provided at the seams for future alteration. Because of the tendency to unravel, it is customary to trim the raw fabric to a wavy or pinked edge.

The machine disclosed herein accomplishes the above and makes it impossible for an operator to trim off more than a narrow strip from the fabric. In machines of the present time, it is necessary for the operator to watch the guiding of the fabric into the machine carefully. If the operator's attention wavers, it frequently happens that the fabric will be cut deeper than desirable and may even spoil the entire article. Furthermore, in machines in use, the cutter is above the work plate and constitutes an ever present danger to the fingers. Because of the tortuous cutting edge, any careless touching of the cutter while in motion draws the fingers into cutting position.

An object of this invention is to devise a machine that will be simple, cheap, positive in action and will only cut off a predetermined narrow strip of fabric. A further object is to devise a machine that will be safe to operate, will present a smooth revolving surface above the workplate and will tend to push out of danger any article or finger laid on the cutting roller.

Other and additional objects will appear as the description proceeds.

Referring to the drawing:

Figure 1 is a side elevation view, partly in section of the machine.

Figure 2 is a detail of the drive.

Figure 3 is a view of a piece of fabric pinked by the machine.

The machine comprises a base 1 of cast iron or other material having legs 2 and 3. Carried by base 1 is a housing 4 in the upper part of which are carried journals 5 and 6. Rotatably mounted in said journals is a drive shaft 7. This drive shaft projects beyond the confines of housing 4 and on the outside thereof carries a pulley 10.

Shaft 7 carries a worm 11 between the journals 5 and 6. A worm gear 12 engaging worm 11 is provided and this gear is rigidly mounted on a vertical shaft 13. Shaft 13 is supported at the bottom in a thrust bearing 15 carried by base 1 and at the top in a bearing 16 carried by a plate 17 rigidly mounted on housing 4.

Near the bottom of shaft 13 is a bevel gear 20 turned thereby and engaging bevel gear 21 carried by horizontal shaft 22. This shaft is carried by bearings 23 and 24 on base 1. Shaft 22

extends out of housing 4 and carries on the end thereof a roller 25 having a flange 26 extending therefrom on one side. Roller 25 is mounted above a slot 28 in base 1 and flange 26 of the roller is adapted to extend into said slot. It will be noted that the line of contact between the smooth roller and cutter is just slightly above the top surface of base 1 and that flange 26 is snug against the inside of cutter 38.

Shaft 22 also carries a gear 30 adjacent bevel gear 21. This gear 30 meshes with a similar gear 31 carried by shaft 32. This shaft is disposed below base 1 and is generally horizontal. One end of shaft 32 is supported in a bearing 33 pivotally mounted at 34 from a pair of lugs 35 (only one of which appears) supported by base 1. Shaft 32 carries a pinking cutter 38 having the usual tortuous cutting edge 39. Shaft 32 is supported at the cutting end by a floating bearing 40. Bearing 40 has pins 41 extending from the sides thereof which ride in recesses 42 of lugs 43 carried by base 1. It will be noted that bearing 40 is movable up and down and is resiliently supported against lugs 43 by arm 45 pivoted at 46 to a member 47 depending from base 1. Arm 45 carries a rigid lever 50 at the end thereof and this lever has a threaded end 51 engaging a screw 52. Screw 52 is turned by knob 53 in sleeve 54 and causes threaded end 51 to travel up and down on it. A housing 60 for the pulley is carried by housing 40.

What is claimed is:

1. A machine of the character described comprising a base, a horizontal shaft mounted above said base, a smooth roller carried by said shaft and having a flange at the inner edge thereof only, said roller extending down near the top of said base and the flange extending down through a slot into said base, a second shaft mounted below said base, a pinking cutter carried by said second shaft and having an active cutting portion extending up through said slot in said base and engaging the smooth surface of said roller and means for turning said cutter to pull fabric through between the roller and cutter, the line of engagement between said cutter and smooth roller being just enough above the base to accommodate the fabric operated upon.

2. A machine of the character described comprising a base, a horizontal shaft mounted above said base, a smooth roller carried by said shaft and having an outwardly extending flange along the inside edge thereof only, said roller extending down near the top of said base with the flange extending through a slot in said base, a second

- shaft mounted below said base, a pinking cutter carried by said second shaft and having an active cutting portion extending up through a slot in said base and engaging the smooth portion of said roller and means for synchronously turning said cutter and roller to pull fabric therethrough, the line of engagement between said cutter and smooth roller being just enough above the base to accommodate the fabric operated upon.
3. A machine of the character described comprising a base, a horizontal shaft mounted above said base, a smooth roller carried by said shaft and having an outwardly extending flange along the inner edge thereof only, said roller extending down near the top of said base with the flange extending through a slot into said base, a second shaft mounted below said base, a pinking cutter carried by said second shaft and having an active cutting portion extending up through said slot in said base to engage said smooth roller, means for mounting said lower shaft whereby the cutter end is adjustable to and from said roller, and means for turning said cutter against said roller to pull fabric through between the cutter and roller, the line of engagement between said cutter and smooth roller being just enough above the base to accommodate the fabric operated upon.
4. A machine of the character described comprising a base, a horizontal shaft mounted above said base, a smooth roller carried by said shaft and having an outwardly extending flange from the inner edge thereof only, said roller extending down near the top of said base with the flange extending through a slot into said base, a second shaft mounted below said base, a pinking cutter carried by said second shaft and having an active cutting portion extending up through said slot in said base and engaging said smooth roller, means for mounting said cutter and shaft whereby said cutter is adjustable to and from said roller, and means for turning said cutter to pull fabric through between the roller and cutter,

the line of engagement between said cutter and smooth roller being just enough above the base to accommodate the fabric operated upon.

5. A machine of the character described comprising a base, a horizontal shaft mounted above said base, a smooth roller carried by said shaft having an outwardly extending flange from the inner edge thereof only, said roller extending down near the top of said base with the flange extending down through a slot into said base, a second shaft mounted below said base, a pinking cutter carried by said second shaft and having an active cutting portion extending up through said slot in said base, means for mounting one of said shafts to permit a predetermined separation of said roller and cutter, resilient means urging said two together, and means for turning said cutter to pull fabric through between the cutter and roller, the line of engagement between said cutter and smooth roller being just enough above the base to accommodate the fabric operated upon.

6. A machine of the character described comprising a base, a horizontal shaft mounted above said base, a smooth roller carried by said shaft and having an outwardly extending flange from the inner edge thereof only, said roller extending down near the top of said base with the flange extending through a slot into said base, a second shaft mounted below said base, a pinking cutter carried by said second shaft and having an active cutting portion extending up through said slot in said base and frictionally engaging said roller surface, means for mounting said cutter shaft to permit a predetermined separation of said cutter from said roller, and means for synchronously turning said cutter and roller to pull fabric therethrough, the line of engagement between said cutter and smooth roller being just enough above the base to accommodate the fabric operated upon.

HARRY C. HERSCHEMAN.
